KRUPP AKTIENGESELLSCHAFT, OF ESSEN-ON-THE-RUHR, GERMANY.

FLUID-BRAKE.

964,485.

Specification of Letters Patent. Patented July 19, 1910.

Application filed February 17, 1906. Serial No. 301,659.

To all whom it may concern:

Be it known that I, FRANZ BÖMINGHAUS, a subject of the Emperor of Germany, and a resident of Essen-on-the-Ruhr-West, Germany, have invented certain new and useful Improvements in Fluid-Brakes, of which the following is a specification.

The present invention relates to the class of fluid-brakes for recoil-guns in which means are provided for regulating the length of recoil.

In the accompanying drawings, one embodiment of the invention is shown by way of example.

Figure 1 shows the brake partly in longitudinal section and partly in side view; Fig. 2 is a section on the line 2—2, Fig. 1, seen from above; Fig. 3 is a section on the line 3—3, Fig. 2, seen from the right; Fig. 4 is a view corresponding to Fig. 2 with changed position of some parts; Fig. 5 is a section on line 5—5, Fig. 2, seen from above, and Figs. 6 and 7 are diagrammatic views.

C is a part of the cradle which remains stationary during the firing. The piston rod B is rigidly secured to the cover c¹ of the cradle through the medium of a flange b¹. The brake-cylinder A is guided in the cradle in such a manner that all the points of the cylinder move in a straight line during the recoil. The piston D is rotatably but non-slidably connected to the piston-rod B and the structure of the piston is approximately that of a hollow cylinder. The connection between the piston and the piston-rod consists of a shoulder d¹ on the piston, a shoulder b² on the piston-rod and a nut b³ which is screwed upon the piston-rod. A projection d² (Figs. 1, 3 and 5) on the piston D engages without play, with a curved groove a¹, cut in the inner wall of the brake-cylinder A.

In the hollow space of the piston D, a slide E (Figs. 2 to 5) is arranged, the shape of which is approximately hollow-cylindrical. The outer surface e¹ of the slide lies tightly against the inner wall d⁴ of the piston D, which wall forms the guiding surface for the slide and extends parallel to the longitudinal axis of the brake. Two passages e³ (Figs. 1 to 4) extend from the hollow space of the slide. Two passages d⁵

(Figs. 1 to 4) in the piston, merge into the guiding surface d⁴ for the slide E. Each 55 of the passages d⁵ communicates with the fluid space toward the head F of the brake-cylinder, through the medium of a groove d⁶ cut in the exterior wall of the piston.

The piston-rod B is provided with a central bore b⁴ (Fig. 1) in which is mounted a rod G. One end of the rod G is rigidly connected with the slide E through the medium of a transverse pin H (Figs. 2, 4 and 5) for which a pair of guide-slots b⁵ (Figs. 65 3 and 5) are provided in the piston-rod B. The slots b⁵ extend parallel to the longitudinal axis of the piston-rod. The end g¹ (Fig. 1) of the rod is provided with screw-threads which engage with the screw-threads 70 of a nut J (Fig. 1) which is rotatably but non-slidably arranged in the cover c¹. The above-described arrangement prevents rotation of the slide E relatively to the piston-rod B and permits of the slide E being adjusted 75 relatively to the piston D in the direction of the longitudinal axis of the brake when the nut J is turned.

When the parts assume the position shown in Figs. 1 to 3, Fig. 5 and position I in Fig. 80 6, and recoil of the brake-cylinder A takes place, the fluid passes from the piston-rod side of the brake-cylinder to the other side of the piston through the hollow space of the slide E, the passages e³ and d⁵ and the 85 grooves d⁶. During the movement of the brake-cylinder the slide E does not change its position but by reason of the curved course of the guide groove a¹ for the projection d², the piston D turns relatively to 90 the slide E. The passages d⁵, therefore, become gradually cut off by the outer surface e¹ of the slide E, that is to say, the area of the passage becomes gradually diminished at the place where the fluid passes from the 95 passages e³ into the passages d⁵, and the fluid becomes throttled to an increasing extent. When finally the passages d⁵, are entirely covered by the outer surface e¹ of the slide E (see position II, Fig. 6) the passage of 100 the fluid is cut off and the recoiling parts, therefore, come to a standstill. This does not, however, take place until the brake cylinder has made its full stroke owing to the dimension of the passages e³, d⁵, and the 105 shape of the groove a¹.

If it is desired to obtain a recoil, the length of which is about half of the normal recoil, the slide E is moved by hand or automatically by means of the nut J, the rod G and the pin H, until the passages e^3 assume approximately the position shown in position III, Fig. 7, relatively to the passages d^5 when the parts are in the position of rest. When the recoil commences the available area for the passage of the fluid is then correspondingly smaller and during the recoil it becomes gradually diminished, and it is entirely cut off, when the passages d^5 assume the position shown in position IV, Fig. 7, relatively to the passages e^3 . The passage of the fluid is then cut off and the recoiling parts come to a standstill.

Any other length of recoil which lies between the shortest permissible and the normal may of course be obtained by suitable adjustment of the slide.

Having thus described my invention what I claim as new therein and desire to secure by Letters Patent is:—

1. In a recoil brake having parts formed with registering openings providing a bypass for the fluid, rotating relatively during recoil to throttle the passage of fluid through said by-pass and adjustable to vary the length of the recoil; means for changing the relative positions of said parts in a direction at an angle to the direction of relative rotation, whereby the point of fluid cut off may be changed at will.

2. A recoil gun having parts provided with registering openings, rotating relatively during recoil to cut off flow of brake fluid and adjustable transversely to such rotation to regulate the point of cut off; one of said openings having a part extending at an angle to the direction of cut off movement whereby the flow is cut off at different points by the previous adjustment of the parts.

3. The combination with a piston provided with a passage through which fluid passes from one side of the piston to the other, of a throttling device for the passage in the piston, adjustable to change the length of the recoil, a hollow piston rod, and a rod axially adjustable within the hollow piston rod and connected with the throttling device to adjust said device to change the recoil.

4. The combination with a piston provided with a passage through which fluid passes from one side of the piston to the other, of a throttling device for the passage in the piston, adjustable to change the length of the recoil, an axially movable rod connected with the throttling device to adjust said device to change the recoil, and a nut suitably journaled against axial movement relatively to the piston and connected to the rod to cause its axial movement.

5. In a fluid pressure brake, the combination of a piston rod, a piston provided with a passage through which fluid passes from one side of the piston to the other, a throttling device for the passage in the piston, arranged between the piston and the piston rod, and adjustable axially of the piston to change the length of the recoil, and means for adjusting said throttling device.

6. In a fluid brake for guns, the combination of a hollow piston provided with a passage through which the fluid passes from one side of the piston to the other, a piston rod, a slide tightly fitting within the piston between the piston and the piston-rod and movable axially therein, said slide being provided with a passage adapted to register with the passage in the piston, and means for adjusting the slide within the piston.

7. In a fluid brake for guns, the combination of a hollow piston provided with a passage through which the fluid passes from one side of the piston to the other, a hollow piston-rod on which the piston is rotatably arranged, a slide tightly fitting within the piston and movable axially therein, said slide being provided with a passage adapted to register with the passage in the piston, and means passing through said piston-rod and engaging said slide for adjusting the slide within the piston.

8. In a fluid pressure brake of the character described, having a slide adjustable axially for varying the throttling effect during recoil; means for imparting axial adjustment to the slide consisting of a rod extending through the piston rod, a pin carried by the end of said rod, working in slots in the piston rod and entering the slide, and a nut threaded on the other end of said rod in position to be accessible from the outside.

9. In a fluid brake for guns, the combination of a piston rod, a piston having a surface parallel to the longitudinal axis of the brake and having openings for the passage of the fluid, a slide movable on said surface of the piston between the piston and the piston rod and having openings adapted to register with the openings in the piston, and means for adjusting the slide relatively to the piston from the outside.

10. In a fluid brake for guns, the combination of an adjustable hollow piston provided with a passage through which the fluid passes from one side of the piston to the other, a guide tightly fitting within the piston, said guide being provided with a passage adapted to register with the passage in the piston and means for effecting a relative axial adjustment between the guide and piston.

11. In a fluid brake for guns, the combination of an adjustable piston having openings for the passage of the fluid, a guide

within said piston parallel to the longitudinal axis of the brake and having openings adapted to register with the openings in the piston, and means for effecting a relative axial adjustment between the guide and piston.

5 The foregoing specification signed at Düs-

seldorf this twenty-ninth day of January, 1906.

FRANZ BÖMINGHAUS.
